SIMON E. SCHROEDER, OF NEWTON, IOWA

SUPPORTING AND DRIVING MECHANISM FOR WRINGERS

Application filed December 12, 1925. Serial No. 75,007.

This invention relates to supporting and driving mechanism for wringers.

The object of the invention is in the provision of a simplified supporting and driving mechanism for wringers.

Another object thereof is in the provision of a driving mechanism for the conventional wringer that positively prevents swinging of the wringer to the various operative positions unless said wringer has the drive portions thereof entirely disengaged from the main drive shaft.

Still another object is in the provision of a simplified driving connection between the conventional vertically disposed drive shaft and the wringer mechanism, whereby said normally vertically disposed drive shaft may be moved to an unclutched position with relation to said wringer mechanism.

20 A further object lies in a simplified means for relating a wringer mechanism to a normally vertically disposed drive shaft to accomplish an optional clutching engagement therebetween by the manual movement of one member from the other.

A still further object is to provide a driving connection for a swingable wringer mechanism, said driving connection including a normally vertically disposed drive shaft adapted, however, for movement to an unclutched position with relation to said wringer mechanism.

A yet further object is in providing a supporting and driving mechanism for wringers, which includes the offsetting of the wringer mechanism with respect to the conventional upright drive shaft, and connections between said wringer mechanism and the drive shaft, which permit swinging of the wringer about its axis only when disengaged from said drive shaft.

Other objects of the invention will appear in the following specification, taken in connection with the annexed drawings, in which—

50 Fig. 1 is a front elevation of my supporting and driving mechanism for wringers, showing same attached to a conventional washing machine, portions thereof being broken away for more detail showing;

Fig. 2 is a cross-sectional view, taken on the line 2—2 of Fig. 1.

Referring to the drawings, I have shown my wringer support and driving mechanism in operative position upon a conventional washing machine structure, of the type usually referred to as the upright oscillator.

Inasmuch as the present application is directed entirely to the driving mechanism, merely a general description of the washing machine is thought necessary. Referring, however, to the washing machine structure, we find a housing member 10, which in a measure forms a part of the supporting frame, inasmuch as it is directly attached, as at 11, to the ordinary leg portions 12. An inner supporting frame for the operating portions of the washer is shown at 13. The washer, as stated before, is of the upright oscillator type, there being provided an oscillating tub portion 14 having a frictional connection 15 with an agitator portion 16. Means for driving the agitator portion 16 is provided in a manner well known in the art, and includes a lever 17, a crank 18, worm gear 19, 20, drive wheel 21, belt 22, and the conventional electric motor 23, suitably attached, as at 24, to the frame 13.

A gear housing 25 encloses the gears, as well as the stub shaft 26, which supports part of the gears. This housing is partially filled with lubricant and is fashioned in a manner to prevent the passage of said lubricant therefrom.

Means for driving the wringer mechanism now to be described, includes a small gear 27 attached to the stub shaft 26, said gear driving a train of gears 28 and 29, providing the driving connection for the wringer structure through the mechanism now to be described.

A housing member is shown at 30, which is slightly larger than the ordinary housing member for the conventional upright driving element, the same in this instance not having as yet been described. At the lower end of the housing 30 is a base portion 31, which is really a part of the gear casing, said base portion including a supporting element 33 for the before mentioned gear 29, which has, upon its upper face, a portion 32 adapted to re-

ceive in a loose manner the lower end 33 of the upright main drive shaft 34. This drive shaft 34 normally is held in a substantially vertical position, as shown in full lines in the drawings. However, due to the loose connection at the lower end of the drive shaft, the latter is adapted to be moved by lever mechanism, later to be described, to a position shown in dotted lines in Fig. 1. At the upper end of the main drive shaft 34 is positively attached a gear 35 adapted to mesh, during the driving connection, with the wringer mechanism later to be described.

Disposed fixedly upon the upper end of housing 30 is a supporting frame 36, which encloses not only the upper end of the main drive shaft, but is also fashioned in a manner to receive the wringer mechanism. In the present instance, the wringer mechanism is not positioned with the clutching portions thereof directly above the main drive shaft, but is rotatably mounted, or rather, has its housing 37 rotatably mounted, as at 38 and 38^a, in the frame 36 and extension 30^a of frame 30, respectively. The housing 37 is fashioned in a somewhat conventional manner, in that it provides also a supporting portion 40 for a wringer member 41, which includes the tensioned roll members 42 and 43. A horizontally disposed shaft 44 provides driving means for the lower wringer roll, and has a bevel gear 45 mounted upon its inner end and meshing with a second gear 46. The gear 46 has disposed therebelow and integrally formed therewith a second gear portion 46^a, the same being adapted to mesh with the before mentioned gear 35 disposed on the upper end of the main drive shaft 34. Means for supporting the above mentioned gears 46 and 46^a is provided in the vertically disposed stub shaft 46^b, the same being supported in a rotatable manner in part 39. An opposed bevel gear 47 also meshes with the gear 46, and is similarly rotatable on the horizontally disposed shaft 44. A conventional clutching element is shown at 48, and a manually controlled lever 49 provides the means for clutching the said member 48 to either of the bevel gears 45 or 47 to accomplish the rotation of the wringer rolls in the direction desired.

The wringer housing 37, previously described as somewhat similar to the ordinary wringer housing, differs in the present instance in that said housing is recessed at 50, 51, 52 and 53 to permit the gear 35 on the upper end of the main drive shaft to be swung into engagement with gear 46^a when said main drive shaft assumes the driving position; in other words, the full line position shown in Fig. 1.

Means for moving the main driving element and the attached gear away from the gear 46, or rather, to an unclutched position in relation thereto, is provided in the following mechanism.

A manually controlled lever 54 is pivotally attached to the frame 36, and to the lever 54 is pivoted an arm 55, which is pivoted at its opposite end to a bearing 56 surrounding the upper end of the main drive shaft. The bearing 56 is adapted to be moved laterally in a slot 56^a in casing 36 by the mechanism just described. In so moving the bearing 56 the upper end of shaft 34 and the gear 35 attached thereto are likewise moved, and gear 35 can thus be thrown into or out of engagement with gear 46^a. The bearing 56 has formed thereon a projection 56^b of the same shape as the recesses 50 to 53, and as shown in Fig. 2, it has shoulders 50^a which engage the sides of the recesses. It will thus be seen that when gears 35 and 46^a are in engagement the member 56^b is positioned in one of the recesses to prevent rotary movement of casing 37 to which the wringer is attached.

It is obvious from the above that the movement of the main drive shaft to a clutched or unclutched position with respect to the wringer mechanism is accomplished by manual movement of the lever 54. Likewise, it is obvious that rotation, or rather swinging, of the wringer mechanism about its axis is prevented as long as the gears 35 and 46^a are in mesh. However, when the main drive shaft is moved to the dotted line position shown in Fig. 1, or in other words, away from the gear 46, the wringer may be moved manually to any of the operative positions. It is emphasized at this time, however, that only when the gears 35 and 46 are in their unclutched position can the wringer be swung about its axis, and that, during the swinging action, there is no connection with the constantly rotating main driving element, and therefore no danger of the wringer being accidentally forcibly rotated about its axis.

Referring to the operation of the driving mechanism, it is thought apparent that the swinging of the wringer about its axis, offset with respect to the main drive shaft, can be effected only when the gear 35 is manually moved away from the gear 46^a, at which time, however, the wringer may be moved to any of the operative positions. Likewise, it may be readily seen that by offsetting the wringer in the manner described herein, the wringer rolls will extend considerably further over the tub than in the conventional wringer mounting, and therefore will be in a more effective position for the rinsing action.

What I claim is:

1. In a machine of the class described, the combination of wringer rolls and driving mechanism therefor including a horizontally disposed shaft, a stub drive shaft, gear connection between the stub shaft and horizontal shaft, a main drive shaft, gear connections between the main and stub drive shafts, means movable with said main drive shaft

- to lock said wringer against swinging movement only when said main and stub drive shafts are engaged and lever mechanism for causing engagement and disengagement of the main and stub drive shafts.
2. In a machine of the class described, the combination of a wringer, and driving mechanism therefor including a main drive shaft, driving connections for the wringer between the latter and said main shaft, means movable with said drive shaft for locking the wringer against swinging movement only when the drive shaft and driving connections are engaged and mechanism for separating the main drive shaft and driving connections to permit swinging movement of the wringer.
3. In a machine of the class described, a substantially vertically disposed drive shaft, supporting means therefor disposed adjacent the upper end thereof, a wringer mechanism, supporting means for said wringer mechanism adjacent the upper end of said drive shaft, a driving connection between the wringer and main drive shaft, means mounted on said drive shaft for locking the wringer against swinging movement when the drive shaft and driving connections are engaged, and means for separating the main drive shaft and wringer to permit swinging movement of the wringer.
4. In a machine of the class described a wringer comprising rolls and a casing therefor, a main drive shaft and a casing therefor, said wringer casing being mounted for swinging movement upon said latter casing, gearing between said drive shaft and rolls for driving the latter from the former, means movable with said drive shaft for engagement with said wringer casing normally locking said wringer casing against swinging movement when said gearing is in engagement, and means for moving said gearing to and from engagement for locking and unlocking said wringer casing against and for swinging movement respectively.
5. In a machine of the class described, a wringer comprising rolls and a casing therefor, a main drive shaft and a casing therefor, said wringer casing being mounted for swinging movement upon said latter casing, gearing between said drive shaft and rolls for driving the latter from the former, means for separating said gearing, and means cooperating with said last mentioned means for locking or releasing said wringer casing when the gearing is engaged or disengaged respectively.
6. In a machine of the class described, the combination with a swinging wringer mechanism movable to a plurality of positions, of a main drive shaft, driving connections between said shaft and the wringer mechanism, said connections comprising a pair of gears mounted on said shaft and said mechanism respectively and arranged to be engaged or disengaged by relative movement of the main shaft with respect to the wringer mechanism, means movable with said shaft for locking said wringer mechanism against swinging movement, and lever mechanism operatively connected to the shaft for disengaging said connections and for moving said means out of locking position to allow swinging movement of said wringer mechanism when the connections are disengaged.
7. A machine of the class described having, in combination, wringer mechanism having a head at one end by which the wringer is supported for movement about a vertical axis to a plurality of positions, a vertical drive shaft having its upper end located eccentric to and alongside of the aforesaid axis of movement of said wringer mechanism, disengageable locking means for said wringer mechanism to prevent or permit pivotal swinging movement of said wringer mechanism at the will of the operator, means providing a detachable driving connection between said vertical drive shaft and said wringer mechanism, and a single control device for operating the last-mentioned means and said locking means.
8. A machine of the class described having, in combination, a wringer mechanism mounted to move about a vertical axis to a plurality of positions, an upright main drive shaft, and driving mechanism connecting said shaft to said wringer mechanism and including an upright stub shaft located coaxially with said vertical axis of the wringer mechanism and adjacent but eccentric to the upper end of said drive shaft.
9. A machine of the class described having, in combination, wringer mechanism arranged to swing about a vertical axis, a main drive shaft located on an axis in offset relation to the aforesaid axis and being arranged to have a lateral movement, and driving connections between said shaft and said wringer mechanism arranged to be connected or disconnected by said lateral movement of said drive shaft.
10. A machine of the class described having, in combination, wringer mechanism mounted to swing about an axis to a plurality of positions, a main drive shaft located at an axis offset with relation to the aforesaid axis and arranged to have lateral movement, disengageable driving connections between said shaft and said wringer mechanism, and means for disengageably locking said wringer mechanism against swinging movement, said driving connections and said locking means arranged to be operated by the said lateral movement of said drive shaft.
11. A machine of the class described having, in combination, a main vertical drive shaft, wringer mechanism mounted to swing about an axis offset with relation to said drive shaft, and disengageable gearing

mounted on said shaft and said wringer mechanism for providing a driving connection therebetween and operable by a horizontal shifting movement of said shaft.

12. A machine of the class described comprising, in combination, a wringer mechanism including a stub shaft, a main drive shaft mounted parallel to said stub shaft, a pair of gears mounted on said stub shaft and said drive shaft respectively and meshing with each other to form a driving connection between said shafts, and means for moving said drive shaft out of parallelism with said stub shaft to effect a disconnection therebetween.

13. A machine of the class described comprising, in combination, a swinging wringer mechanism including a frame having a plurality of slots radially arranged about the axis of swinging, a stub shaft coaxially located with respect to the center of the swinging movement of said wringer, a main drive shaft swingable into and out of a position parallel to said stub shaft, a pair of gears mounted on the respective shafts and arranged to mesh when said shafts are parallel, a member mounted on said drive shaft and arranged to fit in one of said slots when said shafts are parallel, and means for swinging said drive shaft out of parallelism to throw said gears out of mesh and to move said member out of the slot to permit the swinging of the wringer.

In testimony whereof, I have hereunto affixed my signature.

SIMON E. SCHROEDER.
